UNITED STATES PATENT OFFICE

CHESTER A. MACOMIC, OF CHICAGO, ILLINOIS, ASSIGNOR TO PATENT PRODUCTS CORPORATION OF CHICAGO, OF WILMINGTON, DELAWARE, A CORPORATION OF DELAWARE

PATTERN-SETTING MECHANISM FOR TYPE-CASTING MACHINES AND THE LIKE

Application filed November 1, 1928. Serial No. 316,601.

My invention relates to pattern setting mechanism for type casting machines and the like and has for one object to provide in combination with a pattern bed means adapted to be controlled by a typewriter keyboard without interfering with the typewriter operation for setting the pattern pins in the bed in predetermined relation. Another object is to provide in such means an arrangement whereby the setting of the pattern pins is independent of and in nowise affected by different methods of typewriter attachment. Another object is to provide an arrangement whereby failure of the operator to immediately release pressure on the typewriter key will not interfere with the movement of the typewriter or of any of the typewriter controlled pattern setting mechanisms. Other objects will appear from time to time in the specification and claims.

My invention is illustrated more or less diagrammatically in the accompanying drawings, wherein—

Figure 1 is a vertical section through the typewriter keyboard and a part of the pattern bed and pattern pin setting mechanism;

Figure 2 is a section through the plunger carriage along the line 2—2 of Figure 1;

Figure 3 is a view similar to Figure 2 showing the pattern pin depressed;

Figure 4 is a view similar to Figure 3 showing the plunger carriage moved to the second position when the operator failed to release the key.

Like parts are indicated by like characters throughout the specification and drawings.

A is a type setting machine frame. It is provided with a cover or top A¹. On this cover or top A¹ rests a typewriter A² being held adjustably in position thereon by means of the threaded pins A³, nuts A⁴. A⁵ is the typewriter keyboard frame, A⁶ the spacer, A⁷ A⁸ the typewriter keys. These keys are carried by keyboards A⁸ and are of the usual typewriter construction, these keyboards being positioned by a comb plate A⁹.

B is the pattern bed. It is supported in the frame A by means of cross bars B¹ and may be adjustably removably mounted in the frame by any suitable means which are not

here illustrated since they form no part of the present invention. B² B³ are a series of pattern pins slidable longitudinally in the pattern plate. These pins have lower extensions B⁴ adapted to serve as stops for matrix strips there being one pin for each character on the matrix strip, the matrix strip having as many characters as there are characters on the typewriter and there being one matrix strip and therefore one series of pins for each space of typewriter travel. It will be understood that my invention involves the specific elements and means for forcing any one of the matrix pins, for instance, the left hand pin shown in Figure 1 down into a position where it can be engaged by a suitable projection, on one of the matrix strips not here shown to raise the matrix strip in such position that a character thereon selected by the typewriter key will be in line with the casting mechanism. It will be understood that as the typewriter carriage moves along the plunger carriage B⁴ moves in unison with it, being supported by the roller B⁵ traveling along the track bar B⁶.

In order that the typewriter keyboard may maintain control over the plunger carriage as it travels along, no matter what its position, there are provided a series of pivoted shutters C. Each shutter extends transversely of the plunger carriage throughout the entire distance of possible travel of the carriage and each shutter overlies a plunger C¹ in the plunger carriage, the relation of shutter and carriage being such that no matter where the carriage is the shutter if rotated will depress its associated plunger just as shown in Figure 1, at the left hand lower corner. This effect always takes place with every stroke of a typewriter key to cause a shutter to rotate and depress a plunger and to displace a pattern pin. Incidentally it will be noted that there are twice as many pattern pins as there are plungers, the idea being that when the typewriter shift key is operated, the plunger carriage will move longitudinally to bring the plunger into line with the adjacent pattern pin, thus each plunger may control two pattern pins in each line of pins in the pattern bed.

The shutters are operated from the key-board by means of connecting rods D. These rods engage each one of the key bars E⁸, are provided with projections D¹ traveling in the comb plate A⁹, extend down through a guide plate D² to a pivot connection with a bell crank lever D³, which lever is pivoted on the frame and at its other end engages a connecting rod D⁴ extending to one of the shutters C, there being a series of such devices interposed between each separate key bar and each separate shutter.

The plunger carriage is built up of two opposed channel sections tied together by the bracing members E. Extending downwardly from the bottom of the plunger carriage are a series of lugs E¹. A pivot pin E² extends through all these lugs and carries associated with each lug, a guide arm E³ which is integral with and supports the plunger C¹. This guide arm is slotted as at E⁴ and the spring E⁵ tends to hold the forward end of the slot against the pivot pin E². The plunger has a pattern pin engaging finger E⁶ projecting downwardly beyond the guide arm E³. It will be noted that as the plunger carriage and the typewriter carriage travel along in coordination under the influence of the escapement mechanism of the typewriter, it frequently will happen that the operator who is writing on the typewriter will fail to release the typewriter key. This makes no difference so far as the typewriter is concerned because of the striking key bar mechanism but it does result in holding down a plunger during the time that the typewriter carriage and plunger carriage are traveling across the bed of the machine. It is important therefore to provide means to permit such movement of the carriage to take place while the plunger is down without interfering with the proper operation of the machine. Referring now to Figure 2, it will be noted that the plunger is just about to come down and select a pattern pin. In Figure 3 this has taken place. In Figure 4, the operator has not released the typewriter key and therefore not the shutter but the typewriter escapement is operated. The spring E⁵ has been stretched, the plunger stays in place engaging the selected pattern pin and the pivot pin E² is moved to the right in the slot E⁴, a distance equal to the carriage escapement and no harm is done. As soon as the operator releases the key, the shutter will fly up, the spring E⁵ will raise the plunger and at the same time return the guide arm or lever back to the position of Figures 2 and 3 ready for the next operation. If this release arrangement were not provided, it will be obvious that the pattern pin selecting finger would either engage the next pattern pin and bend it or break it off or if the pin were strong enough, the typewriter escapement would not be able to operate, either of which

contingencies would be fatal to the successful operation of the machine.

Claims:

1. The combination with a pattern bed having a plurality of movable pins, of a key board controlled mechanism for longitudinally displacing selected pins, including a movable carriage and a pin engaging member yieldingly supported thereon. 70

2. The combination with a pattern bed having a plurality of movable pins, of a key board controlled mechanism for longitudinally displacing selected pins, including a movable carriage and a pin engaging member yieldingly supported thereon and means for permitting limited movement of the carriage to take place while the pin selecting member remains in engagement with a pin. 80

3. The combination with a pattern bed having a plurality of movable pins, of a key board controlled mechanism for longitudinally displacing selected pins, including a movable carriage, a pin engaging member loosely mounted thereon and a spring adapted to yieldingly position such member in its loose support. 85

4. The combination with a pattern bed having a plurality of movable pins, of a key board controlled mechanism for longitudinally displacing selected pins, including a movable carriage, a pin engaging member loosely mounted thereon and a spring adapted to yieldingly position such member in its loose support, the direction in which said spring acts being inclined to the pin selecting member. 95

5. The combination with a pattern bed having a plurality of movable pins, of a key board controlled mechanism for longitudinally displacing selected pins, including a movable carriage, a pin engaging member loosely mounted thereon and a spring adapted to yieldingly position such member in its loose support, the direction in which the spring acts being inclined to the direction of movement of the carriage. 105

6. The combination with a pattern bed having a plurality of movable pins, of a key board controlled mechanism for longitudinally displacing selected pins, including a movable carriage, a pin engaging member loosely mounted thereon and a spring adapted to yieldingly position such member in its loose support, the direction in which the spring acts being inclined to the direction of movement of the carriage and to the direction in which the selecting member acts. 115

7. The combination with a pattern bed having a plurality of movable pins, of a carriage movable thereacross, a pin engaging member loosely pivoted on the carriage, means for moving the member into engagement with selected pins and yielding means for withdrawing it therefrom. 120

8. The combination with a pattern bed

- having a plurality of movable pins, of a carriage movable thereacross, a pin engaging member loosely pivoted on the carriage, means for moving the member into engagement with selected pins and yielding means for withdrawing it therefrom, the pin engaging member comprising a lever slotted at one end, and a pin engaging finger projecting downwardly from the lever at the other end, a pin on the carriage loosely engaging the slot and a spring interposed between the carriage and the lever and adapted to normally hold the lever in a rest position with the pin engaging one end of the slot. 5
- 10 9. The combination with a pattern bed having a plurality of movable pins, of a carriage movable thereacross, a pin engaging member loosely pivoted on the carriage, means for moving the member into engagement with selected pins and yielding means for withdrawing it therefrom, the pin engaging member comprising a lever slotted at one end, and a pin engaging finger projecting downwardly from the lever at the other end, a pin on the carriage loosely engaging the slot and a spring interposed between the carriage and the lever and adapted to normally hold the lever in a rest position with the pin engaging one end of the slot, the slot 15 extending in the direction of carriage movement.
- 10 10. The combination with a pattern bed having a plurality of movable pins, of a carriage movable across the bed, a lug projecting downwardly from the carriage, the carriage being slotted, a pin engaging member comprising a slotted lever, a pivot pin carried by the lug and loosely engaging the slot in the lever, a pattern pin engaging finger 20 projecting downwardly from the opposed end of the lever, an arm projecting upwardly from the last named end of the lever through the slots in the carriage.
- 10 11. The combination with a pattern bed having a plurality of movable pins, of a carriage movable across the bed, a lug projecting downwardly from the carriage, the carriage being slotted, a pin engaging member comprising a slotted lever, a pivot pin carried by the lug and loosely engaging the slot 25 in the lever, a pattern pin engaging finger projecting downwardly from the opposed end of the lever, an arm projecting upwardly from the last named end of the lever through the slots in the carriage and yielding means adapted to hold the lever in the rest position with the pin engaging finger out of contact with the pin and with the pivot pin engaging the end of the slot nearest to 30 the pin engaging finger.
- 10 12. The combination with a pattern bed having a plurality of movable pins, of a keyboard controlled mechanism for longitudinally displacing selected pins, including a movable carriage, a pin engaging member loosely mounted thereon and means adapted to yieldingly position such member in its loose support.
13. The combination with a pattern bed having a plurality of movable pins, of a key board controlled mechanism for longitudinally displacing selected pins, including a movable carriage, a pin engaging member loosely mounted thereon and means adapted to yieldingly position such member in its loose support, the direction in which said spring acts being inclined to the pin selecting movement of the member. 70
14. The combination with a pattern bed having a plurality of movable pins, of a key board controlled mechanism for longitudinally displacing selected pins, including a movable carriage, a pin engaging member loosely mounted thereon and means adapted to yieldingly position such member in its loose support, the direction in which the means act being inclined to the direction of movement of the carriage. 75
15. The combination with a pattern bed having a plurality of movable pins, of a key board controlled mechanism for longitudinally displacing selected pins, including a movable carriage, a pin engaging member loosely mounted thereon and means adapted to yeildingly position such member in its loose support, the direction in which the means act being inclined to the direction of movement of the carriage and to the direction in which the selecting member acts. 80
16. The combination with a pattern bed having a plurality of movable pins guided for longitudinal movement, of a keyboard controlled mechanism for longitudinally displacing selected pins, including a movable carriage and a pin engaging member pivoted thereto. 85
17. The combination with a pattern bed having a plurality of movable pins guided for longitudinal movement, of a keyboard controlled mechanism for longitudinally displacing selected pins, including a movable carriage and a pin engaging member loosely pivoted thereto. 90
18. The combination with a pattern bed having a plurality of movable pins guided for longitudinal movement, of a keyboard controlled mechanism for longitudinally displacing selected pins, including a movable carriage and a pin engaging member loosely pivoted thereto, and means for yieldingly positioning said member in normally constant relation to its pivot point. 95
19. The combination with a pattern bed having a plurality of removable pins, of a keyboard controlled mechanism for longitudinally displacing selected pins, including a movable carriage and a pin engaging member pivoted in relation thereto, said member including a horizontal arm portion, having a pin engaging element at one end thereof, 120
- 65

the opposite end of said arm being slotted for loose pivotal engagement with the carriage.

20. The combination with a pattern bed having a plurality of removable pins, of a keyboard controlled mechanism for longitudinally displacing selected pins, including a movable carriage and a pin engaging member pivoted in relation thereto, said member including a horizontal arm portion, having a pin engaging element at one end thereof, the opposite end of said arm being slotted for loose pivotal engagement with the carriage, and yielding means for normally moving the horizontal arm portion as far in the direction of normal movement of the carriage, as the slot will permit.

Signed at Chicago, county of Cook, and State of Illinois, this 18th day of October, 1928.
